UNITED STATES PATENT OFFICE.

LEWIS C. BAYLES, OF EASTON, PENNSYLVANIA, ASSIGNOR TO INGERSOLL-RAND COMPANY, OF JERSEY CITY, NEW JERSEY, A CORPORATION OF NEW JERSEY.

FLAT VALVE.

Application filed August 26, 1925. Serial No. 52,526.

This invention relates to pressure fluid rock drills, but more particularly to an improved plate valve having a circumferential fin outside of the port area, whereby the unbalancing of the valve can be insured and the speed of its action increased.

One of the objects of the invention is to provide for a plate valve of the oscillating type in which a greater area subject to reduced pressure can be obtained alternately at each end of the valve without the use of a shifting fulcrum.

Further objects of the invention will hereinafter appear, and the invention is illustrated in one of its preferred forms in the accompanying drawings, in which

Figure 1 is a longitudinal sectional elevation partly broken away of so much of a rock drill as will serve to make the invention clear,

Figure 2 is a transverse sectional view on the line 2—2 of Figure 1 looking upwardly in the direction of the arrows, and

Figure 3 is a detailed transverse sectional view through the valve showing the cut away or relieved portions of the circumference referred to as fins in this application.

Referring to the drawings, the cylinder A is provided with a piston B having the forward extension or shank C extending through the front cylinder washer D. The cylinder is provided with an exhaust port E controlled by the piston and located in the drawing centrally of the cylinder. The valve F is arranged in the valve chamber G in the head block H, and between the valve and the cylinder is located the cylinder head plate J having the inlet port K leading directly to the back end of the cylinder and the inlet port L communicating with the passage O in the cylinder leading to the inlet port P at the forward end of the cylinder.

The valve F, for convenience of illustration, is shown in the form of a thin circular disk uniformly tapering on its upper or outer side from the median line or diameter Q to the peripheries S and R at each end. For convenience in explanation the two ends of the valve will be referred to by the letters designating their peripheries, as the end S and the end R.

The under or opposite side of the valve is provided with a fulcrum T from which point there is a substantially uniform taper in opposite directions as far as the periph-

eries R and S. The valve may or may not be under cut or recessed as indicated at c and d to lighten the valve, but at the points e and f the valve is substantially under cut as far as the peripheries R and S, thus providing for fins at each end. These under-

60 cut portions or fins e which are the main features of my invention are provided to eliminate the need of a shifting fulcrum in order to secure quick and positive valve 65 action. Each functions alternately with the other, as the wing of the valve opposite to it starts to close under reduced pressure beneath it, and its purpose is to hasten the closing by reducing the opposition which, 70 in this case, is the area of the other wing of the valve which is subject to live pressure. The fin causes a substantial portion of this area to be subjected to balanced pressure, 75 whereas without the use of the undercut 75 portion the whole half of the wing to be opened would be subjected to live pressure bearing down upon it, as will be more fully described later in the specification. The

valve chamber G in the head block H is 80 circular in form and sufficient clearance is provided between the valve and the walls of the chamber to permit free oscillation of the valve.

The valve may be guided in any suitable 85 manner as by means of the pins U extending into sockets V in the valve with sufficient clearance to permit freedom of movement of the valve.

The back head W of the rock drill is provided with the throttle valve X controlling the supply of live pressure fluid to the valve chamber G.

In the operation of the device let it be assumed that the piston is at the end of its 90 forward stroke and travelling rearwardly as indicated in Figure 1. The live pressure fluid in the valve chamber G holds the valve in the position indicated and live pressure fluid is admitted over the periphery R of the 100 valve to the inlet port P at the forward end of the cylinder to drive the piston rearwardly. After the piston closes the exhaust port E, compression in the rearward end of the cylinder is built up to act upon the inner 105 face of the valve at the closed end S through the port K. At the same time the fin e at the closed end S of the valve is subject to balanced pressure, being acted upon on both sides by live pressure fluid at line pressure. 110

When the piston B overruns and again opens the exhaust port E to the forward end of the cylinder, the pressure is reduced or dropped beneath the end R of the valve over the entire surface from the fulcrum to the periphery R, including the fin f. This drop in pressure tends to pull down the end R of the valve and thereby throw the valve, and is counteracted only by the live pressure on the top of the end S. This pressure is not applied to the entire surface, however, as the fin e, being under cut as shown, is subject to a balanced pressure. Hence the valve F is placed in an unbalanced condition, the reduced pressure of end R acting on a greater area than the live pressure acting on the end S, the difference being the area of the fin e or f. At the same time pressure fluid trapped in the head of the cylinder by the upward stroke of piston B acts upon the under side of the end S of the valve F through the port K and will tend to force the end S up and close the end R. Thus, as a result of these three conditions occurring simultaneously, the valve is oscillated or thrown with great speed and positiveness, and pressure fluid is admitted into the rear end of the cylinder through port K, forcing piston B downwardly and causing repetition of the valve action.

I am not to be understood as limiting the

invention to the precise form and details of construction shown in the drawings, particularly in the matter of the shape of the valve, which is shown as circular, but which can be square, oval, or in any shape which lends itself to oscillation.

I claim:

1. A fluid actuated rock drill comprising a cylinder and a reciprocating piston, a valve chamber having ports communicating with opposite ends of the cylinder, and a fluid actuated distributing valve having wings adapted to cooperate with the said inlet ports, said wings having reduced undercut extensions or fins at opposite ends outside of the areas of the said ports.

2. A fluid actuated rock drill comprising a cylinder and a reciprocating piston, a valve chamber adjoining said cylinder having ports leading to opposite ends of said cylinder for the distribution of motive fluid thereto, an oscillating distributing valve having two wings adapted to control the admission of pressure fluid to the cylinder through the said ports and reduced undercut portions on the said wings integral therewith and located oppositely to each other and outside of the areas of the said ports.

In testimony whereof I have signed this specification.

LEWIS C. BAYLES.
